UNITED STATES PATENT OFFICE.

RUDOLF CARL, OF BUFFALO, NEW YORK.

LAST.

No. 918,506.

Specification of Letters Patent. Patented April 20, 1909.

Application filed December 15, 1908. Serial No. 467,606.

To all whom it may concern:

Be it known that I, RUDOLF CARL, a citizen of the United States, residing at Buffalo, in the county of Erie and State of New York, 5 have invented a new and useful Improvement in Lasts, of which the following is a specification.

This invention relates to an articulated sectional last which is adapted to support a 10 shoe while the same is being manufactured and which may also be used for insertion in a manufactured shoe for the purpose of displaying the same or preventing the same from becoming wrinkled or creased.

15 My invention relates more particularly to a sectional last of this character in which the fore and heel parts are yieldingly held by spring pressure in their normal operative position and which can be folded or collapsed sufficiently to permit of more readily withdrawing a shoe therefrom or inserting the same into and removing the same from a shoe.

It is the object of this invention to produce 25 a last having this capacity which, when compared with those heretofore in use, is much stronger and durable in construction and can be produced at a lower cost.

In the accompanying drawings consisting 30 of 2 sheets: Figure 1 is a side elevation of a sectional last embodying my invention.

Fig. 2 is a vertical longitudinal section of the same. Fig. 3 is a horizontal section thereof. Figs. 4 and 5 are detached perspective views of the heel part and the fore 35 part of the last, respectively.

Similar numerals of reference indicate corresponding parts throughout the several views.

40 The fore part 1 and the heel part 2 of the last which are usually constructed of wood have the same general shape as the corresponding parts of the last heretofore in use, the novelty in the present invention residing 45 more particularly in the means whereby these sections are pivotally connected and yieldingly held in a normal or operative position relatively to each other. The preferred construction of this pivotal connection 50 between the two sections of the last shown in the drawings is as follows: 3 represents a substantially semi-cylindrical groove formed transversely or horizontally in the rear face or end of the fore part of the last 55 between its top and bottom thereof so as to form upper and lower stop faces or shoul-

ders 4, 5, on this end of the fore part above and below the transverse groove, as shown in Figs. 1, 2 and 5. On the front end of the heel part the same is provided on opposite sides with two forwardly projecting pivot or hinge knuckles, lugs or ears 6, 7. The front sides or faces of these pivot knuckles are of semi-cylindrical form, the axis of the same being arranged transversely or horizontally relatively to the heel part of the last. These knuckles or lugs are arranged between the top and bottom of the heel part so as to form upper and lower stop faces or shoulders 8, 9, on the front end of this part 70 which are adapted to coöperate with the upper and lower shoulders of the fore part, respectively. The pivot knuckles are preferably constructed integrally with the heel part of the last and turn with their curved 75 or semi-cylindrical faces in the correspondingly-shaped sockets formed by opposite ends of the groove in the fore part of the last. 10 represents the eye of a metal screw eye which is enlarged and flattened and arranged against the inner side of one of the pivot or hinge knuckles and fastened with its screw or threaded shank 11 into the fore part of the last at the bottom of the transverse groove thereof and between opposite 80 sides of the fore part of the last. 12 represents a horizontal pintle, pin or rod which passes transversely through openings formed concentrically in the knuckles of the heel part and through the eye 10 of the screw 11, 85 as shown in Figs. 1, 2 and 3, thereby forming a pivotal connection between the fore and heel parts of the last.

Owing to the large bearing surface between the knuckles of the heel part and the 90 sockets of the fore part, these parts are reliably held in place relatively to each other, thereby insuring proper shaping of the shoe which is fitted upon the same or the shoe into which the same may be inserted. Furthermore, this construction is very strong and durable and is not likely to break under the strains to which the same is ordinarily subjected and inasmuch as the knuckles are formed integrally with the heel part the cost 100 of the last on this account is materially reduced. The distance between the two pivot lugs or knuckles is such that when the screw eye engages the inner side of one of said knuckles, an intervening space is left between the other side of the screw eye and the other knuckle.

13 represents the coil of a spring whereby the parts of the last are yieldingly held in their normal operative position. This coil is arranged in the intervening space between 5 the screw eye and the knuckle against which the screw eye does not bear and surrounds that part of the pivot pin within this space. The opposite ends of this spring coil extend 10 upwardly on the front and rear sides of the pivot pin in the form of arms 14, 15 which are preferably seated in upright grooves 16, 17 formed in the opposing upper faces of the fore and heel parts of the last section, respectively, as shown in Fig. 2. The upper 15 ends of the front and rear spring arms are preferably bent forwardly and rearwardly, respectively, in the form of hooks or spurs 18, 19 which engage with recesses 20, 21 formed in the fore and heel parts of the last 20 section at the upper ends of the grooves thereof, respectively, as shown in Fig. 2. In applying this spring to the last sections, the coil of the same is preferably compressed in a direction lengthwise of its axis, so that the 25 resilience of the same while engaging the inner side of the screw eye and that knuckle which is not engaged by the screw eye causes the other knuckle to be firmly drawn with its inner side against the outer side of the screw 30 eye, thereby reliably holding the last sections in the proper position relatively to one another in a direction transversely of the last. When free, the resilience of the spring in a circumferential direction causes its arms to 35 spread or separate the fore and heel parts of the last above the pivotal connection between the same and to engage the lower shoulders between these parts below said connection, as shown in Figs. 1 and 2. This is the position 40 the parts of the last assume while a shoe is being built upon the same or while the last is inserted within a previously manufactured shoe to keep the same in shape.

For the purpose of withdrawing the last 45 from the shoe or detaching the shoe from the last, the two sections of the same are turned one relatively to the other, so that the shoulders or faces of the fore and heel parts above the pivotal connection between the same approach 50 each other while the opposing faces or shoulders of these parts below this pivot are separated, thereby folding or shortening the last in a manner common to this type of last and permitting a shoe which has just 55 been made on the last to be easily stripped from the same or permitting this last to be easily inserted into or removed from a previously manufactured shoe for keeping the same in shape or for displaying the same in 60 show windows or stores.

I claim as my invention:

1. An articulated sectional shoe last comprising a fore part provided on its rear end with semi-cylindrical sockets, a heel part 65 having semi-cylindrical knuckles fitting in

said sockets, means for pivotally connecting said fore and heel parts concentrically with the sockets and knuckles thereof comprising a screw eye secured with its screw to the rear end of the fore part while its eye bears 70 on one of its sides against the inner side of one of said knuckles and its opposite side is out of engagement from the inner side of the other knuckle and a pintle passing concentrically through said knuckles and eye, and a spring for holding said fore and heel parts 75 in their normal position and also exerting an axial pressure for holding said eye against the respective knuckle which is engaged by the eye. 80

2. An articulated sectional shoe last comprising a fore part provided on its rear end with semi-cylindrical sockets, a heel part having semi-cylindrical knuckles fitting in 85 said sockets, means for pivotally connecting said fore and heel parts concentrically with the sockets and knuckles thereof comprising a single screw-eye secured with its screw to the rear end of the fore part while its eye bears on one of its sides against the inner side of 90 one of said knuckles and its opposite side is separated by an intervening space from the inner side of the other knuckle, a pintle passing concentrically through said knuckles and eye, and a spring for holding said fore and 95 heel parts in their normal operative position and having a coil which is arranged in said space and is connected at opposite ends with the fore and heel parts. 100

3. An articulated sectional shoe last comprising a fore part provided on its rear end with semi-cylindrical sockets, a heel part having semi-cylindrical knuckles fitting in 105 said sockets, means for pivotally connecting said fore and heel parts concentrically with the sockets and knuckles thereof comprising a single screw eye secured with its screw to the rear end of the fore part while its eye bears on one of its sides against the inner side of 110 one of said knuckles and its opposite side is separated by an intervening space from the inner side of the other knuckle, a pintle passing concentrically through said knuckles and eye, and a spring for holding said fore and heel parts in their normal operative position and having a coil which is arranged in 115 said space and which has arms projecting upwardly from the opposing ends of the fore and heel parts above the pintle having grooves which receive said arms. 120

4. An articulated sectional shoe last comprising a fore part provided on its rear end with semi-cylindrical sockets, a heel part having semi-cylindrical knuckles fitting in 125 said sockets, means for pivotally connecting said fore and heel parts concentrically with the sockets and knuckles thereof comprising a screw eye secured with its screw to the rear end of the fore part while its eye bears on one of its sides against the inner side of 130

one of said knuckles and its opposite side is separated by an intervening space from the inner side of the other knuckle, a pinhole passing concentrically through said knuckles and eye, and a spring for holding said fore and heel parts in their normal operative position and having a coil which is arranged in said space and which has front and rear arms projecting upwardly from its opposite ends and spurs projecting forwardly and rearwardly from the upper ends of the front

and rear arms, respectively, the opposing faces of the fore and heel parts being provided with upright grooves which receive said arms and recesses at the upper ends of 15 said grooves which receive said spurs.

Witness my hand this 12th day of December, 1908.

RUDOLF CARL.
